UNITED STATES PATENT OFFICE.

EDWARD H. STINES, OF NEW BRUNSWICK, NEW JERSEY, ASSIGNEE TO PERFECTION MANUFACTURING COMPANY, OF NEW BRUNSWICK, NEW JERSEY, A CORPORATION OF NEW JERSEY.

THREAD-GUIDE.

1,271,492.

Specification of Letters Patent. Patented July 2, 1918.

Application filed December 9, 1918. Serial No. 136,008.

To all whom it may concern:

Be it known that I, EDWARD H. STINES, a citizen of the United States, residing at New Brunswick, in the county of Middlesex and State of New Jersey, have invented certain new and useful Improvements in Thread-Guides, of which the following is a specification.

I have invented an improvement in thread guides for textile mechanisms, particularly knitting machines.

My principal object is to design a thread guide which is simple in construction and yet capable of being readily adjusted to threads of varying sizes, and of being securely held in the desired position; and in which the thread cannot get caught or tangled and broken.

This and other objects and advantages of my invention will appear from the following specification, taken in connection with the accompanying drawings; and the novel features of my improvement will be precisely defined in the appended claims. This disclosure, however, is to be construed as explanatory only, and variations in the device actually shown may be made to the full extent indicated by the general and specific terms in which the claims are expressed.

On the drawings:

Figure 1 is a view showing how my thread guide construction is mounted for use;

Fig. 2 is a top plan of an improved thread guide element utilized in the practice of my invention;

Fig. 3 is a transverse section of the element; and

Fig. 4 is a sectional view of a detail, taken on the line 4—4 of Fig. 2, the observer looking in the direction of the arrows.

The same numerals identify the same parts throughout.

In the particular description of a thread guide made according to my invention, I employ the numeral 1 to indicate the stem of an ordinary knitting machine, bearing a collar 2, having affixed to it a plurality of members 3, which constitute means for supporting certain elements whereby the guiding of the thread is immediately effected. See Fig. 1. Each of the members 3, which

are in the form of radiating arms or rods, will bear a single adjustable thread guide element, such as a disk 4, upon its outer end; and as the members 3 are identical; likewise the disks 4; only one of them needs to be portrayed herein.

The disk 4, best shown in Figs. 2 and 3, is adjustably mounted on the rod 3; and this result is gained by flattening the end of the rod; which may be in the form of a piece of stout wire; and riveting it to the center of the disk 4. The disk is thus rotatably secured in place. I also provide a number of openings 5 of different sizes through the disk 4; and by properly grading these openings, threads of varying thicknesses can be successfully worked. An operator can turn the disk by taking hold of it with his hand and shifting it till the proper opening is in the required position; and in order to make the manipulation easy, the disk may have a number of projections 6 on its circumference to enable it to be grasped to advantage. These projections are preferably scallop-shaped; but obviously any form of projection will answer; and in some cases an ordinary milled edge will serve the same purpose.

The openings 5 are suitably arranged around the center of the disk 4; and the disk will have means, such as catches 7, for maintaining it in its different positions. The catches 7 are not shown in Fig. 1, on account of the small scale upon which the parts appear in that figure; but they are fully illustrated in the remaining views. Each of these catches is constituted of two portions 8 of the disk, each portion being located between two parallel cuts 9. There will thus be twice as many pairs of these cuts as there are openings 5; and each pair of cuts will be adjacent the periphery of the disk and will extend chordally of the same; that is to say, in the same direction as the chord of an arc which lies across a radius of a portion 8 between its respective cuts 9. Each portion 8 will be bent away from the disk, and each pair of adjacent portions 8 make a notch or recess 10 into which the rod 3 will fit. This feature is most clearly

illustrated in Fig. 4. When the disk and rod are assembled, the rod is caused to bear against the lower face of the plate from the center to the circumference; and when the 5 disk is turned, the cut and bent portions 8 of each catch will yield enough to allow the rod to enter the recess 10 between them and be engaged by the portions 8 with sufficient tightness to prevent relative displacement of 10 the catch and the rod. The entire disk 3, with its openings 4, its projections 6 and catches 7, can be made in one operation; and the cost of manufacture is therefore but little; nevertheless, a very efficient thread 15 guide element is produced.

I also attach to the rod 3 a guard 11, which extends over the edge of the disk toward the center thereof, and rests at its end upon the disk and over the rivet in the end 20 of the rod 3. This guard will keep the thread from ever getting caught between the disk and the arm 3, whenever any slackening of the thread occurs.

In practice, each disk 4 and rod 3 will be 25 located above a bobbin or spool of thread 12, supported by the stem 1; and the particular opening 5 of the disk which is in use will be directly over the axis of the bobbin immediately below it. From the disk the 30 thread passes through a fork 13, and over a hook 14; both the fork and the hook being supported by a casing 15 on the stem 1. The fork is pivotally mounted on a bar 16 affixed to the casing 15, and engages a guard 35 17 at the outer extremity of this bar. The thread is held between the fork 13 and the guard 17; and the opposite end of the fork has a projection 18 which engages an arm 19 on a shaft or spindle 20, by which the 40 hook 14 is carried. This spindle is actuated by a suitable device (not shown), in the casing 15 to hold the fork against the guard; and after leaving the hook 14, the thread passes certain parts of the machine which 45 control stop mechanism, below the hook 14. Should the tension on the hook 14 become too great, the device above mentioned is overcome and the shaft 20 is actuated to release the fork 14. The thread can 50 then drop clear of the fork; and all tension ceases, thus allowing the stop mechanism, not shown, to operate; and the running of the machine is thus interrupted until the operator gives it the necessary 55 amount of attention. The parts above-mentioned and designated by the numerals 13 to 20 inclusive, well known to those skilled in this art, need not be fully set forth.

The disks 4 on the rods 3 are individually 60 adjustable; and neither the rods 3 nor the collar 2 need be moved in order to shift the disks so as to bring the desired opening into line with the axis of the bobbin 12 below it. Whenever another opening is to be made

ready for use the disks can be turned accordingly in an instant simply by manipulating them as above stated. The collar 2 and rods 3 remain fixed and stationary, and the catches 8 engage and disengage the rods 3 automatically, so that both the turning 70 and the locking of the disks can be done at one and the same time.

The openings 5 will intercept knots or bunches on the thread or yarn, and produce such tension as is needed to cause the thread 75 to swing the hook 14 to move the shaft 20 and release the fork 13. If a bunch or knot should strike the fork 13 and be intercepted, a similar result will follow. It has been 80 found that sometimes a bunch or knot in the thread will get past the fork 13 without the thread being stretched enough to release the fork; but with the guide disk 4, such a mishap never occurs. The thread from the bobbin travels straight through 85 the disk, and the openings are just large enough to permit the easy passage of thread of the proper thickness. Hence, any unusual thickness at once chokes up the opening and subjects the thread to tension, thereby stopping 90 the machine and obviating delays that accidents such as the breaking of the thread might entail.

The edge of each opening 5 is punched up to a slight extent, so as to present a 95 smooth curved surface to the thread passing through it.

Having described my invention, what I believe to be new and desire to secure and protect by Letters Patent of the United 100 States is:—

1. In a thread guide construction, the combination of a supporting member, a disk rotatably mounted thereon, said disk having circumferential projections to enable 105 it to be manipulated and a plurality of graded openings arranged around its center, said disk also being provided with cut and bent portions constituting catches to engage the member and hold the disk in various 110 positions, and a guard secured to said member and extending across the edge of the disk toward the center thereof.

2. A thread guide construction comprising a perforated rotatable disk, means for mounting said disk, and a guard for the disk secured to said means and projecting over the edge of said disk toward the center of same.

3. A thread guide construction comprising a disk and means for rotatably mounting said disk, the disk having a plurality of yieldable portions constituting catches to engage said means and hold the disk in various 120 positions.

4. A thread guide construction comprising a disk and means for rotatably mounting the disk, said disk having a plurality of 125

cut and bent portions adjacent its periphery to engage said means and hold the disk in various positions.

5. In a thread guide construction, a rotatable disk having a plurality of pairs of chordally-extending cuts adjacent its periphery, the portions of the disk between the cuts of each pair being bent away from the

disk, each pair of portions constituting a catch, and means for supporting said disk, 10 to be engaged by said catches.

In testimony whereof, I have signed my name to this specification this 27th day of November, 1916.

EDWARD H. STINES.
